Attorney

UNITED STATES PATENT OFFICE.

MARY A. MEEKER, OF WINCHESTER, MASSACHUSETTS.

HOOP.

1,266,699.

Specification of Letters Patent.

Patented May 21, 1918.

Application filed April 23, 1917. Serial No. 164,034.

To all whom it may concern:

Be it known that I, MARY A. MEEKER, a citizen of the United States, residing at Winchester, in the county of Middlesex 5 and State of Massachusetts, have invented certain new and useful Improvements in Hoops, of which the following is a specification, reference being had to the accompanying drawings.

10 This invention relates to certain improvements in hoops and it is an object of the invention to provide a novel and improved device of this general character which will be attractive to the eye and which is also 15 provided with means whereby sound may be created by the hoop when rolling.

The invention consists in the details of construction and in the combination and arrangement of the several parts of my improved hoop whereby certain important advantages are attained and the device is rendered simpler, less expensive and otherwise more convenient and advantageous for use, all as will be hereinafter more fully set 25 forth.

The novel features of the invention will hereinafter be definitely claimed.

In order that my invention may be the better understood, I will now proceed to describe the same with reference to the accompanying drawings, wherein is illustrated a view in elevation of a hoop constructed in accordance with an embodiment of my invention.

20 As disclosed in the accompanying drawings, H denotes a hoop of any ordinary or preferred construction and of any desired dimensions and D denotes a disk positioned at the axial center of the hoop and of a major diameter less than the mean diameter 25 of the hoop H. The opposite faces of the disk D are provided with suitable designs of different colors so that the hoop when rolling will attract the eye.

30 The marginal portions of the disk D are provided with the circumferentially spaced openings defined by conventional eyelets 1. M denotes an elongated flexible member preferably of wire which is threaded through alternate eyelets 1 and through the openings 2 provided in the hoop H, said openings 2 being circumferentially spaced and in radial alinement with the eyelets 1 of the disk D through which the member M is threaded. The member M serves to maintain the disk D in proper position within

the hoop H as is believed to be clearly indicated in the drawings and the portions of the member M intermediate the openings 2 of the hoop overlie the periphery of the 60 hoop. It is also to be noted that each pair of strands 4 of the member M coacting with an eyelet 1 is threaded through a single opening 2.

Disposed through the eyelets 1 intermediate the eyelets through which the member M is threaded are the rings 3 which bridge the periphery of the disk D. Loosely disposed through the rings 3 are the rings 3' and loosely engaged with the rings 3 are 70 the bells B or other sounding members. This particular mounting of the bells B permits the bells, when above the horizontal plane intersecting the axial center of the disk D, to overlie said disk so that as the 75 bells pass above such horizontal plane the bells will drop or swing below the periphery of the disk and which action further facilitates the sounding of the bells. The portions of the member M overlying the periphery of the hoop H and which extends circumferentially thereof substantially in continuity to afford a tread member whereby a slight lateral movement or inclination of the hoop is afforded to facilitate the 85 sounding of the bells B upon rolling of the hoop. This particular mounting of the bells B permit the bells when above the horizontal plane intersecting the horizontal disk D to overlie said disk so that as the bells pass 90 above the horizontal plane intersecting the horizontal disk, the bells will drop or swing below the periphery of the disk and which action further facilitates the sounding thereof.

95 From the foregoing description, it is thought to be obvious that a hoop constructed in accordance with my invention is of an extremely simple and comparatively inexpensive nature and is particularly well 100 adapted for use by reason of the convenience and facility with which it may be assembled, and it will also be obvious that my invention is susceptible of some change and modification without material departure 105 from the principles and spirit thereof and for this reason I do not wish to be understood as limiting myself to the precise arrangement and formation of the several parts herein shown in carrying out my invention in practice, except as hereinafter 110 claimed.

I claim:

1. A device of the character described comprising a hoop provided with circumferentially spaced openings, a disk positioned within the hoop and having its marginal portion provided with circumferentially spaced openings, a member threaded through the openings of the hoop and certain of the openings of the disk for maintaining the disk in applied position within the hoop, the openings of the hoop being substantially in radial alignment with the openings in the disk through which the flexible member is threaded, each pair of strands of the members coacting with an opening in the disk being disposed through a single opening in the hoop, the portions of the member intermediate the openings of the hoop overlying the periphery of the hoop and extending circumferentially thereof substantially in continuity and affording a tread member, rings disposed

through the remaining openings of the disk bridging the periphery thereof, a second series of rings loosely directed through the first named rings, and bells loosely engaged with said last named rings. 25

2. A device of the character described comprising a hoop, a disk positioned within the hoop and supported thereby, said disk being provided in its marginal portion with circumferentially disposed openings, rings disposed through said openings and bridging the periphery of the disk, a second series of rings loosely engaged with the first named rings, and bells loosely engaged with the last named rings. 30

In testimony whereof I hereunto affix my signature in the presence of two witnesses.

MARY A. MEEKER.

Witnesses:

SARAH McLEAN,
BELLE L. SARGENT.
